CLAIM

The ornamental design of a connector insert, as shown and described.

DESCRIPTION

This design application is related to U.S. utility application Ser. No. 11/015,403 filed Dec. 17, 2004, entitled “Connector Insert for Preventing Contamination”, to the same inventors, which is incorporated herein by reference, and having been filed concurrently with the present design application.

FIG. 1 is a perspective view of a connector insert according to the present invention;

FIG. 2 is a left side view thereof;

FIG. 3 is a front view thereof;

FIG. 4 is a back view thereof;

FIG. 5 is a top view thereof; and,

FIG. 6 is a bottom view thereof.

The broken lines in the drawings are for illustrative purposes only and form no part of the claimed design.
